UNITED STATES PATENT OFFICE.

GEORGE K. FLOWER, OF PITTSBURG, PENNSYLVANIA.

MOWING-MACHINE.

SPECIFICATION forming part of Letters Patent No. 724,275, dated March 31, 1903.

Application filed October 30, 1901. Renewed January 12, 1903. Serial No. 138,627. (No model.)

To all whom it may concern:

Be it known that I, GEORGE K. FLOWER, a citizen of the United States, residing at Pittsburgh, in the county of Allegheny and State of Pennsylvania, have invented certain new and useful Improvements in Mowing-Machines, of which the following is a specification, reference being had therein to the accompanying drawings, forming part of this specification, in which—

Figure 1 is a plan view of a portion of my improved mowing-machine bar. Fig. 2 is a similar view, the blade-guides having been removed. Fig. 3 is a longitudinal sectional view on the line III III of Fig. 1. Fig. 4 is a cross-sectional view on the line IV IV of Fig. 3. Fig. 5 is a side view in elevation of one of the fingers or guards detached. Fig. 6 is a cross-sectional view corresponding to Fig. 4, but showing the guards composed of one piece and provided with upper portions corresponding to the blade-guide, but made integral with the main guide. Fig. 7 is a plan view similar to Fig. 1, but showing the knife in a different position at the commencement of the cutting operation in one direction, the position of the knife at the approximate termination of the operative portion of the stroke being indicated in dotted lines.

My invention consists of an improvement in mowing and reaping machinery, and refers more particularly to the guards for the knife or sickle and means incorporated therewith by which the grass or other crop being cut may be partially severed by the upper portion of the finger or guide in advance of the knife and may be collected and assembled with relation to the stationary cutting edges, so that the action of the knife is facilitated, the most powerful portion of its stroke utilized to the best advantage, and the operation generally rendered more positive, accurate, and with less trouble, due to the clogging of the parts by accumulation of grass, &c., than heretofore.

Referring now to the drawings, 2 represents the usual finger or guard commonly employed on machines of this character, a series of which guards are secured to a stationary bar 3 by means of bolts 4 or otherwise, such fingers being provided with suitable ways in which is mounted the vibrating bar 5, carry-

ing the usual knife or sickle 6, which rests upon the upper face of the stationary knife-plate 7, against the edges 8 of which the 55 tapered edges of the knives or sickles bear in the operation of shearing in the manner well understood.

In the usual construction of this class of mechanism the fingers or guards 2 are provided with an upper rearwardly-extending shield or fender 9, adapted to protect the knife-blades and to provide an upper edge on each side against which the grass, &c., may bear under the action of the knife. The 65 width of such fingers is usually somewhat narrower than the width of the stationary knife or ledger plate 7, and practically the full length of the cutting edges of the shears or sickles is utilized during the larger portion 70 of the stroke in both directions, the result of which is that the points 10 of the knife not only have to perform the hardest part of the work by reason of the fact that some of the grass is forced forward toward the point and 75 accumulated there in a dense collection and also that a greater amount of grass is embraced between the points and the back of the knives, but during such portion of the stroke, coming, as it does, at or about the limit of the forward 80 and back stroke of the knife-bar, the knife thereby receives its movement from the actuating-crank when it is approximately about at its dead-center. This is a serious disadvantage and is one which my present improvement is designed to overcome. Furthermore, by reason of the excess of work thus being thrown upon the point of the knife frequent regrinding becomes necessary and the wear is not proportionate through- 90 out, thus considerably shortening the available life of the knife. A further disadvantage is that by reason of the tapering formation of the fingers or guards the grass is forced toward the point and away from the knife 95 and is apt to lean or slant under such action, so that it is not, therefore, cut off as close to the ground as it would be if it was at all times maintained in an erect or perpendicular position, or approximately so. It is therefore desirable to provide free travel of the knife at each end of the stroke before commencing to cut, so that the cleaning of the knives and freeing of the accumulated grass

from them may be facilitated. These disadvantages are overcome in my present invention by the use of upper supplemental plates or guards 11, either secured upon the upper 5 surface of the usual fingers or guards 2, as shown in the principal figures of the drawings, or by forming the main guard 2 in one piece and providing it with outwardly-extending lateral edges corresponding to the edges of 10 the plate 11, as clearly shown in Fig. 6. This plate approximately conforms to the shape of the mowing-machine guard, extends forward, and terminates in a sharp point 12. The upper edges are sloped backwardly and 15 outwardly to a point 13 somewhat back of the approximate line of the points of the knives, at which point the plate-guard is widest and at which point it extends considerably beyond the edges 8 of the stationary 20 knife 7 at each side. Back of such point the plate is considerably narrowed, being curved in on each side, as shown, brought within the width of the cutting edges 8, and extending back into a rear guard 14, approximating in 25 position and shape the usual shield or fender 9. The result of this construction is that in its forward travel through the grass it will force the grass away on each side beyond the lateral stationary cutting edges 8 until it 30 travels back to the point 13, when it will fall back against the stationary cutting edge in a position to be sheared, so that the main cutting action will be performed by that portion of the knife between the points indicated by the letters *a b*, as shown in Fig. 7, 35 during the time when the stroke of the actuating-crank is strongest, and thus relieving the points from the excessive wear which I have described.

40 It will be seen that before the knife commences to cut it will have considerable momentum, due to the fact that the cutting operation is comprised and accomplished within a less portion of its stroke, which portion 45 is the middle portion, while the stroke itself may be also considerably increased, due to the fact that the point of the knife may travel outwardly on each side a distance equaling the amount of difference between the width 50 of the lower fender and that of the upper plate-guard without exposing the knife-point. This difference is clearly illustrated in Figs. 1 and 2 and is indicated by the distances represented by the letters *x* and *z*, respectively.

55 The tapering edges of the plate 13 are ground or filed off, so as to provide sharp edges 15, which in the forward travel of the machine will cut or partially cut tangled grass, heavy stalks, weeds, &c., thus relieving 60 the work of the knives and greatly facilitating the operation.

In the form shown in Fig. 6 the edges 15 may be sharpened by hollow-grinding the guards at an angle, as indicated by the line 65 *c c*, thus insuring the same beneficial result immediately back of the point 13. The upper plate 6 (or when made integral the upper

back sloping portions of the guard) is preferably provided with a series of notches 16, adapted to engage the blades of grass, so as to more securely hold them against the action of the knife.

As thus constructed my invention overcomes the serious difficulties which I have described and in practice has proved itself to be desirable, efficient, and valuable for the purposes in view in a high degree, and the invention will be appreciated by all those accustomed to this class of machinery. It is very simple and inexpensive in construction and operation, not liable to get out of order, and increases the efficiency of the machine.

Various changes and modifications may be made by the skilled mechanic in the design, proportions, or other details of construction without varying from my invention, and I do not desire to be limited to the exact form shown and described, but to include all such changes as within the scope of the following claims.

What I claim is—

1. In a mowing-machine a knife-guard provided with an upper supplemental plate having lateral cutting edges tapering toward the point extending beyond the knife-guard at each side, and provided with a back narrower portion.

2. In a mowing-machine a knife-guard provided with an upper supplemental plate having lateral cutting edges tapering toward the point extending beyond the knife-guard at each side and provided with a back narrower portion and means for arresting and holding the grass.

3. In a mowing-machine the combination of a knife-guard provided with a stationary knife, a tapering vibrating shear-knife and an upper portion projecting beyond the stationary knife for a portion of its length, at each side in the direction of travel of the vibrating knife.

4. In a mowing-machine the combination of a knife-guard provided with a stationary knife, a tapering vibrating shear-knife and an upper portion projecting beyond the stationary knife for a portion of its length at each side in the direction of travel of the vibrating knife, and tapered toward the point.

5. In a mowing-machine, the combination of a knife-guard provided with a stationary knife, a tapering vibrating shear-knife, and an upper guard portion projecting beyond the stationary knife for a portion of its length at each side in the direction of travel of the vibrating knife, such upper guard portion being tapered toward its point, and provided with lateral cutting edges.

6. In a mowing-machine the combination of a knife-guard provided with a stationary knife, a tapering vibrating shear-knife, and an upper guard portion projecting beyond the stationary knife for a portion of its length at each side in the direction of travel of the vibrating knife, such upper guard portion be-

ing tapered toward its point, and provided with means for arresting and holding the grass.

7. In a mowing-machine the combination of 5 a knife-guard provided with a stationary knife, a tapering vibrating shear-knife, and an upper guard portion projecting beyond the stationary knife for a portion of its length at each side in the direction of travel of the 10 vibrating knife, such upper guard portion being tapered toward its point, and provided with notches on its upper edges immediately back of its widest portion.

8. In a mowing-machine, the combination 15 with a knife-guard provided with a stationary

ledger-plate and a vibrating shear-knife; of an upper portion projecting beyond the ledger-plate for a portion of its length, at each side in the direction of travel of the vibrating knife, tapered toward one end, provided with 20 shoulders, laterally-recessed portions, and notches in such recessed portions immediately back of the shoulders.

In testimony whereof I affix my signature in presence of two witnesses.

GEORGE K. FLOWER.
